US00D936641S

(12) **United States Design Patent** (10) Patent No.: **US D936,641 S**
(45) Date of Patent: **** Nov. 23, 2021**

(54) **STAND FOR TELEVISION RECEIVER**

(71) Applicant: **LG ELECTRONICS INC.**, Seoul (KR)

(72) Inventors: **Yooseok Kim**, Seoul (KR); **Younsoo Kim**, Seoul (KR); **Hyoungwon Kim**, Seoul (KR); **Younghun Jang**, Seoul (KR); **Youngwon Jeong**, Seoul (KR)

(73) Assignee: **LG ELECTRONICS INC.**, Seoul (KR)

(**) Term: **15 Years**

(21) Appl. No.: **35/509,457**

(22) Filed: **Feb. 27, 2019**

(80) **Hague Agreement Data**

Int. Filing Date: **Feb. 27, 2019**

Int. Reg. No.: **DM/208201**

Int. Reg. Date: **Feb. 27, 2019**

Int. Reg. Pub. Date: **May 29, 2020**

(30) **Foreign Application Priority Data**

Aug. 29, 2018 (KR) 30-2018-0040279

(51) **LOC (13) Cl.** **14-03**

(52) **U.S. Cl.**

USPC **D14/239**

CPC **G06F 1/1601** (2013.01)

(58) **Field of Classification Search**

USPC D14/125–135, 239, 371, 136, 374–377, D14/440, 450, 448, 336, 342, 159; D21/329, 515, 577, 622, 333, 433, 448, D21/452, 450, 331, 505

CPC ... G06F 1/1601; G06F 1/1643; H05K 5/0004; H05K 5/0017; H05K 5/02; H05K 5/0217
